UNITED STATES PATENT OFFICE.

EMANUEL M. HACKER, OF NEW YORK, N. Y., ASSIGNOR OF ONE-HALF TO M. GOLDMAN & CO., OF NEW YORK, N. Y., A FIRM.

DESIGN FOR TEXTILE FABRIC.

42,138.

Specification for Design.

Patented Feb. 6, 1912.

Application filed December 2, 1909. Serial No. 531,108. Term of patent 3½ years.

To all whom it may concern:

Be it known that I, EMANUEL M. HACKER, a subject of the King of Hungary, and resident of the borough of the Bronx, city, county, and State of New York, have invented a new, original, and ornamental Design for Textile Fabrics, of which the following is a specification.

Reference is to be had to the accompanying drawing showing a section of textile fabric embodying my new design.

The design consists in making the fabric with plaits which are broken in their length instead of being continuous.

I claim—

The ornamental design for a textile fabric, as shown and described.

EMANUEL M. HACKER.
